UNITED STATES PATENT OFFICE.

WILLIAM PHILLIP SMITH, OF TUCSON, ARIZONA.

CONDIMENT HOLDER.

Application filed June 4, 1926. Serial No. 113,717.

This invention relates to condiment holders of the type which are designed to separately contain a plurality of condiments of different kinds and the invention has particular reference to the means for separately or simultaneously dispensing the contents thereof.

Primarily the invention contemplates a condiment holder of the type specified which includes a simple, inexpensive and efficient dispensing mechanism composed of a minimum number of working parts capable of ready assembly or disassembly, whereby to facilitate cleansing of the same or replacement of worn or broken parts.

The invention further comprehends a dispensing mechanism for condiment holders of the type specified including means for rendering the same readily detachable from the body of the holder which body is preferably of glass and breakable, whereby the said mechanism may be applied to a second body in event of such breakage.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

35 In the drawings—

Figure 1 is a plan view of a condiment holder constructed in accordance with the invention;

Fig. 2 is a side view thereof;

Fig. 3 is a vertical sectional view therethrough taken approximately on the line 3—3 of Fig. 1;

Fig. 4 is a perspective view of a portion of the dispensing mechanism;

Fig. 5 is a collective perspective of the valve elements thereof removed;

Fig. 6 is a perspective view of the partition element and valve leaf seat.

Referring to the drawings by characters of reference, the condiment holder includes a body 10 preferably of glass, which is subdivided by a substantially vertical partition 11 into compartments 12 and 13, the partition extending from the bottom wall 14 to the upper open end or neck 15. The partition is so arranged as to render the compartment 13 of greater capacity than the compartment 12 so that the condiment which is used in larger quantities and more frequently, such as salt, may be contained in the 60 larger compartment, and the condiment which is used in smaller amounts and less frequently, such as pepper, may be contained in the smaller compartment.

The dispensing mechanism consists of a substantially cylindrical head 16, which is formed with an outer peripheral flange or bead 17 at its lower end designed to fit over the upper open end or neck 15 of the body 10 and removably retained in place by an attaching ring or annulus 18, which is inferiorly threaded at 19 to engage the exterior threads 20 of the neck 15. The ring is formed with an annular rabbet 21 designed to receive the flange 17 and clamp the same for snugly connecting the head 16 to the body 10. The upper end of the head 16 is exteriorly threaded at 22 to receive the interiorly threaded depending flange 23 of a cap 24 having dispensing openings 25 therein through which the contents of the compartments are sifted.

In order to provide means for selectively preventing the dispensing of the contents of one compartment while allowing for the sifting of the contents of the other compartment, the head 16 is sub-divided by a vertical partition 26 in its lower portion, the lower end of which partition is grooved at 27 to fit over the upper end of the body partition 11. The partition 26 is permanently secured to the head 16. The upper end of the partition 26 is formed with an arcuate groove 28 to constitute a seat for a leaf spring 29 and for bearing knuckles 30 and 31 of the substantially semi-circular shaped valve leaves 32 and 33. The bearing knuckle 30 extends from one edge of the valve leaf 32 to approximately the center thereof and from this point is provided with an axially extending reduced hinge pin 34, while the bearing knuckle 31 extends from the opposite edge of the valve leaf 33 and is provided with an axial bore 35 for the reception of the hinge pin 34. Each bearing knuckle 30 is provided with an extension 37, which extensions protrude through vertical notches 38 in the cylindrical head 16, which notches are disposed in alignment with the partition 26. The extending portions 37 are bent laterally and formed with manipulating knobs 39 disposed exterior of the cylindrical head 16 to

permit of the manual swinging of the valve leaves downwardly to an open relation to allow for the dispensing of the contents of the holder body compartments. In order to 5 removably retain the valve leaf bearing knuckles in the seat 28 and at the same time to sub-divide the upper portion of the head and close the notches 38, a partition element 40 is provided, the under edge of which is 10 formed with a semi-circular groove 41 adapted to overlie and bear on the bearing knuckles 30 and 31. The under side of the cap engages with and clamps the partition element 40 in place and friction on the bearing 15 knuckles is increased or decreased by the threading action of the cap on the cylindrical head 16. The partition element has formed integral therewith, a ring or annulus 42 the external diameter of which is of a size 20 to snugly fit within the head 16 to form valve leaf seats, the leaf spring 29 functioning to normally swing the valve leaves upwardly to a closed position where they engage with the under side of said annulus.

25 In use it is obvious that manipulation of the knobs 39 selectively permits of the dispensing of the contents of either compartment, while manipulation of both to open the valve leaves allows for the sifting out 30 of the contents simultaneously.

To fill the container body or to allow for the application of the dispensing mechanism to a new container body in event of breakage of the original one, it is only necessary 35 to unscrew the ring or annulus 18 to detach the mechanism.

When it is desired to cleanse the mechanism, the same may be readily disassembled by removing the cap 24, which causes the 40 partition element 40 to release and permit removal of the valve leaves 32 and 33.

From the foregoing it will thus be seen that an extremely simple, yet highly efficient condiment holder has been devised 45 which is sanitary and effectual.

What is claimed is:

1. In a condiment holder, a body having a closed lower end and an open upper end, a partition sub-dividing the body into compartments for separately containing different condiments, a head comprising a cylindrical wall mounted on the upper open end of the body, a clamping ring detachably associating the head with the body, a partition in the lower end of the head, having a grooved lower end, fitting over the body partition, valve leaves having aligned bearing knuckles seated on the upper end of said head parti-

tion, means underlying the valve leaves for normally swinging the same upwardly to a closed position, internal abutment elements in the head for limiting the upward movement of the valve leaves, extensions formed on the valve-bearing knuckles disposed exteriorly of the head for swinging the valve leaves to an open position, a perforated sifter cap detachably associated with the upper end of the head, and means adjustably clamped between the cap and the upper portion of the valve-bearing knuckles for holding the same in place, regulating the frictional bearing of the same, and for subdividing the upper portion of the head into compartments corresponding to the lower portion and to the body compartments. 75

2. In a condiment holder including a body, a partition sub-dividing the same into a pair of compartments, a head having a partition correspondingly subdividing the lower portion of the same, and a removable cap on said head having sifter openings, swingable valve elements for each head compartment, and means interposed between the removable cap and the head partition for subdividing the upper portion of the head and for retaining the valve elements in mounted relation to the head partition. 80

3. In a condiment holder including a body, a partition sub-dividing the same into a pair of compartments, a head having a partition correspondingly subdividing the lower portion of the same, and a removable cap on said head having sifter openings, swingable valve elements for each head compartment, and means interposed between the removable cap and the head partition for subdividing the upper portion of the head and for retaining the valve elements in mounted relation to the head partition, the said removable cap when applied retaining said means in place and when removed releasing said means. 85

4. In a condiment holder, including a body, a partition sub-dividing the same into a pair of compartments, a head having a partition correspondingly subdividing the lower portion of the same, and a removable cap on said head having sifter openings, swingable valve elements for each head compartment, and means interposed between the removable cap and the head and for retaining the valve elements in mounted relation to the head partition, the said means having elements defining valve abutment devices. 100 105 110
